UNITED STATES PATENT OFFICE.

THOMAS SPACIE, OF HOUSTON, TEXAS.

SKATE.

No. 825,771.

Specification of Letters Patent.

Patented July 10, 1906.

Application filed July 11, 1905. Serial No. 269,153.

To all whom it may concern:

Be it known that I, THOMAS SPACIE, a citizen of the United States, and a resident of Houston, in the county of Harris and State of Texas, have invented a new and Improved 5 Skate, of which the following is a full, clear, and exact description.

This invention relates to skates; and it consists, substantially, in the details of construction and combinations of parts hereinafter 10 more particularly described, and pointed out in the claims.

The invention has reference more especially to "parlor" or roller skates, though equally 15 applicable in part to the ordinary "runner-skates," and one of the principal objects of the invention is to provide a skate which is simple in its embodiment and comparatively inexpensive to manufacture, besides being 20 thoroughly effective and reliable in use and possessing the capacity for long and repeated service.

A further object is to provide simple means 25 for the attachment to the skate and the detachment therefrom of each set of rollers ordinarily employed adjacent an end thereof, as will hereinafter appear.

The above and additional objects are attained by means substantially such as are 30 illustrated in the accompanying drawings, in which—

Figure 1 is a bottom plan view of a skate having my improvements embodied in connection therewith. Fig. 2 is a longitudinal 35 sectional view on the line 2 2 of Fig. 1. Fig. 3 is a view in perspective of the supporting plate for the rollers employed at the forward portion of the foot-plate of the skate. Fig. 4 is a perspective view in detail of the forward 40 end portion of the foot-plate of the skate to indicate more clearly the special construction thereof. Fig. 5 is a longitudinal sectional view showing the application to the foot-plate of the skate of an ordinary runner for 45 the skate, and Fig. 6 is a view in details showing the construction of certain features of the improvement.

Before proceeding with a more detailed description it may be stated that in the form of 50 my improvements herein shown I preferably provide the skate with a foot-plate of special construction, but embodying in connection therewith substantially similar devices for attaching the skate to the sole and heel of a

shoe, as are described and shown in the former Letters Patent granted to me on the 12th day of April, 1904, and having No. 757,240. Special means are employed for securing to the underside of the foot-plate of the skate the forward set of rollers for the skate, and other 55 special means are employed for also attaching to the under side of the foot-plate the rearward sets of rollers employed for the skate, and while I have herein represented my improvements in a certain preferred embodiment 60 it will be understood that I do not limit myself thereto in precise detail, since immaterial changes therein may be made coming within the scope of my invention.

Reference being had to the drawings by 70 the designating characters thereon, 1 represents the foot-plate of the skate having at the forward end thereof a downwardly and forwardly extending projection 2, having therein a vertical elongated slot 3, it being observed on 75 reference to Fig. 6 that the said downwardly and forwardly extending projection 2 is reduced in thickness at 3^a from the inner side thereof for that portion of the projection below the lower edge of the slot 3 and for a distance substantially equal to the width of the slot, as indicated. At a suitable distance 80 rearwardly of the forward end thereof the foot-plate is provided with a centrally-located opening 4, which is formed by striking 85 out a part of the metal of the foot-plate, forming a rearwardly-extending depression 5 in the upper face of said metal leading from the rear edge of said opening.

In connection with the under side of the 90 forward portion of the foot-plate 1 I employ a plate 6, (shown in detail in Fig. 3,) which is slightly dished or concaved from end to end thereof (see Fig. 2) and which is provided at suitable points of its opposite side edges with 95 laterally-extending offsets 7, it being mentioned that this plate and said offsets thereof are constructed of spring metal, so that when applied to the under side of the foot-plate, as about to be described, it will be at once seen 100 that a vertically-cushioned support is had for the forward set of rollers from the said foot-plate. The forward end of this plate 6 is constructed with a nose-piece 9, having an extension 10 for entering the notch 3 from 105 the inner side of the downwardly and forwardly extending projection 2 of the foot-plate, while the edge portion 11 of the nose-

piece is snugly received between the sides of the vertically-elongated notch formed by the hereinbefore-mentioned reduced portion 3^a of the said projection 2. The plate 6 is also provided at its rearward end with what may be termed a "spring-hook" 12, which is inserted through the opening 4 from the under side of the foot-plate, and on reference to Fig. 2 it will be seen just in what manner the said 10 plate 6 serves to support the forward set of rollers 13, which are mounted on a shaft 14, having its bearings in suitable parallel hangers 15, pendent from the opposite side edges of the plate 6. In virtue of the dished or 15 concave form of the plate it is apparent that an elastic action or effect will be produced between said plate and the foot-plate 1 when the skate is in use.

The foot-plate 1 of the skate is provided at 20 the rearward or heel portion thereof with an opening 16, the portion of the metal of the foot-plate immediately adjacent to the forward edge of said opening being sunken at 17, thus to form in the upper surface of the 25 foot-plate a depression 18, corresponding with the depression 5 before mentioned. Entering the opening 16 from the under side of the foot-plate is a spring-hook 19, formed integrally with the smaller dished or concaved 30 plate 20, having a downwardly and rearwardly extending projection 21, corresponding substantially in every respect with the hereinbefore-mentioned downwardly and forwardly extending projection 2, said plate 35 20 being provided at its rearward edge with a nose-piece 22, having identically the same character of connection between the same and the projection 21 as has already been described in reference to the nose-piece 9 of the 40 plate 6 and said projection 2. The plate 20 is also provided at suitable parts of its edges with offsets 23, corresponding to the offsets 7 of the plate 6, and pendent from the opposite edge portions thereof are parallel hangers 24 45 for supporting the shaft 25 of the rearward set of rollers 26 for the skate.

In Fig. 5 I have shown the plates 6 and 20 as dispensed with, and in lieu of which is employed a runner 27 for the skate substantially 50 of the form shown and described in my former Letters Patent referred to, said runner being provided with an upwardly-extending portion 28, the rearward edge of which is abutted by the forward edge of the 55 base of the depression 5 in the foot-plate, thus to assist to hold the runner in the desired position with reference to the foot-plate, any suitable means being provided at the forward and rearward ends of the latter for effecting 60 attachment therewith of the corresponding ends of the runner.

In Figs. 1, 2, and 5 I have represented substantially the same devices for securing the 65 skate to the sole and heel of a shoe as are described and shown in my former patent and

to which no special reference is to be made herein except to state that said devices are indicated in entirety at 29 in Figs. 2 and 5.

From the foregoing it is thought that the construction and operation of each of the herein-described attachments for the skate will be fully understood, and it will be seen that my improvements possess decided advantages for the purposes for which they were devised. It will thus be seen also that the 70 plates 6 and 20 are each readily detachable from the foot-plate 1 and that they are attachable thereto by springing them into place, with the hooks 12 and 19 thereof resting flush with the upper surface of the foot-plate. 80

Having thus described my invention, I claim as new and desire to secure by Letters Patent—

1. In a skate, a foot-plate having openings therethrough in the forward and heel portions thereof, respectively, the material of said plate having a depression therein from the rearward edge of one of said openings and a similar depression from the forward edge of the other openings. 85

2. A skate, comprising a foot-plate having an opening in the forward portion thereof, and formed with a forwardly and downwardly extending projection having a vertical slot therein, said opening having a depression 95 leading therefrom, the material of this projection being reduced in thickness below the slot to form a groove, and a roller-supporting plate for attachment to the under side of the foot-plate, having a nose-piece partially received in said slot and said groove and formed with a hook extending through the opening and received in said depression. 100

3. A skate, comprising a foot-plate having an opening in the forward portion thereof, and formed with a forwardly and downwardly extending projection having a vertical slot therein, said opening having a depression leading therefrom, the material of this projection being reduced in thickness below the slot to form a groove, and a roller-supporting plate for attachment to the under side of the foot-plate, having a nose-piece partially received in said slot and said groove and formed with a hook extending through the opening 115 and received in said depression, said roller-supporting plate being of concave form and provided with lateral offsets bearing against the under side of the foot-plate. 110

4. A skate, comprising a foot-plate having an opening in the forwardly portion thereof, and formed with a forwardly and downwardly extending projection having a vertical slot therein, said opening having a depression leading therefrom, the material of this projection being reduced in thickness below the slot to form a groove, and a roller-supporting plate for attachment to the under side of the foot-plate, having a nose-piece partially received in said slot and said groove and formed with a hook extending through the opening 125 and received in said depression. 130

a hook extending through the opening and received in said depression, said second-named plate being provided with parallel hangers supporting therein the forward rollers for the skate.

5. In a skate, a foot-plate having an opening in a suitable portion thereof and formed with a depression leading from the edge of said opening, and a roller-supporting plate having 10 a spring-tongue extending through said opening and received in said depression.

6. A skate, comprising a foot-plate having a downward and rearwardly extending projection formed therein with a slot and a groove, 15 the plate being also formed with an opening and a depression leading from the opening, and a plate for the support of the rearward rollers of the skate, having a spring-tongue extending through said opening and resting 20 in the depression and also provided with a nose-piece partially received in said slot and said groove of said projection.

7. A skate, comprising a foot-plate having a downward and rearwardly-extending projection formed therein with a slot and a groove, 25 the plate being also formed with an opening and a depression leading from the opening, and a plate for the support of the rearward rollers of the skate, having a spring-tongue extending through said opening and resting in 30 the depression and also provided with a nose-piece partially received in said slot and said groove of said projection, the roller-supporting plate being dished from end to end thereof and provided with lateral offsets bearing 35 against the under side of the foot-plate.

In testimony whereof I have signed my name to this specification in the presence of two subscribing witnesses.

THOMAS SPACIE.
